VAPORIZER.

Application filed June 1, 1926. Serial No. 112,898.

This invention relates to vaporizers which form a part of refrigerating apparatus and in which refrigerant vaporizes to absorb heat from a chamber to be maintained at a predetermined low temperature.

An object of my invention is to provide a flooded type of vaporizer which is formed of a plurality of sections detachably secured in endwise relation, the sections being selected 10 from variable standard lengths, so that a vaporizer of desired length can be economically and readily formed.

Another object of the invention is to provide a vaporizer for refrigerating apparatus, 15 in which the major portion is formed of a relatively small section and refrigerant area without reducing the heat transferring capacity thereof.

A further object of the invention is to provide a vaporizer for refrigerating system consisting of elongated communicating sections which can be readily assembled, and which will withstand the pressure of the refrigerant therein.

These and other objects of my invention will appear in the following description of an embodiment of my invention.

In the drawings, Fig. 1 illustrates a longitudinal sectional view of a vaporizer embodying my invention. Fig. 2 is an enlarged vertical sectional view of the same, taken on line 2-2 of Fig. 1. Fig. 3 is an enlarged vertical sectional view of the vaporizer, taken on line 3-3 of Fig. 1. Fig. 4 is an end view of 35 the vaporizer, and Fig. 5 is an enlarged sectional view of the brace within the reduced section of the vaporizer.

Referring to the drawings by characters of reference, the vaporizer is preferably made 40 up of two sections indicated at A and B, which are removably secured together, the section A being standard in form, and the section B being of desired cross section and length to efficiently transfer heat from chambers of varying area and length. The section A of the vaporizer includes an annular cuprous casing or shell 10, which is open at both ends. An end closure ring 11 is provided with a peripheral annular recess 12, within

50 which one end of the casing is pressed and se-

cured by solder 13 to provide a leak proof connection capable of withstanding the refrigerant pressures internally of the casing. The end closure ring 11 is provided with a central aperture 14, which is closed by a plate 15 removably secured against the exterior face of the closure ring by bolts 16. Refrigerant inlet and outlet passages 17 and 18 extend through the closure plate 15 and couplings 18^a and 19 are secured in the exterior ends thereof 60 to provide connections for the high and low pressure refrigerant conduits of a refrigerating system of the compressor, condenser, evaporator type.

The plate 15 is provided with a hub 20 which extends through the aperture 14 interiorly of the casing 10 and the refrigerant inlet passage 17 extends therethrough and opens into the interior of the casing 10. The outlet end of the passage 17 is of reduced area and is controlled by a ball valve 21. A float 22 is pivotally mounted within the casing 10 upon an arm 23, which is pivotally mounted to the inwardly extending portion 20 of the closure plate. A flat spring member 25 is secured to the lower portion of the arm 23 and is arranged to maintain the ball valve 21 adjacent its seat. An outlet tube 26 is arranged to extend within the inner end of the passage 18, and the open upper end thereof projects above 80 the upper level of the liquid refrigerant and lubricant within the casing 10 and provides an outlet for the refrigerant which vaporizes within the casing 10. The outlet tube 26 is in open communication with the passage 18, which in turn is connected by coupling 19 with the suction or return line of the refrigerating apparatus. The tube 26 is provided adjacent its upper end with openings 27, which are arranged at the upper level of the lubricant 85 within the casing 10.

The structure so far described is a flooded type of vaporizer, in which liquid refrigerant is maintained at substantially a constant level, and lubricant of lighter specific gravity 95 than the refrigerant travels freely through the entire circuit. Due to the differences in the specific gravity, the major portion of the lubricant in the casing 10 will float upon the refrigerant and will flow by gravity into 100

the suction conduit through the openings 27 in the outlet tube, so that substantially a constant quantity of lubricant is maintained within the casing 10. The structure so far described is substantially the same as that illustrated in my pending application, Serial No. 475,344, filed June 6th, 1921, and the connection with a refrigerating apparatus and the function and operation of the elements so far described are fully set forth therein, and a further description is, therefore, not deemed necessary to a full understanding of this invention.

A closure ring 28 is arranged at the open end of the casing 10 and is provided with a peripheral annular groove 29, within which the end of the casing 10 is pressed and secured by solder 30, so as to provide a leak-proof joint which will withstand the pressure of the refrigerant within the casing 10 when expanded. The section B of the vaporizer is removably attached to the ring 28 and such section may be of various standard lengths and diameters, so that a standard section A 25 can be utilized with varying sizes of vaporizer sections, as shown at B. The section B is materially reduced in cross section relative to section A of the vaporizer and is so designed to permit its assembly with a smaller area 30 and to reduce the quantity of refrigerant naturally required in the vaporizer when the vaporizer in its entirety is of the same section as A.

The section B of the vaporizer consists preferably of a cylindrical cuprous casing or shell 31, which can be formed in desired diameters and lengths. An annular beading 32 is formed to extend exteriorly of the casing 31 and provides a stop member for the flanged 40 supporting ring 33, which is assembled around the end portion of the casing. The end 34 of the casing is flanged outwardly against the adjacent end face of the flanged supporting ring and is suitably sealed there- 45 against to prevent leakage of the refrigerant. The flanged portion 35 of the ring 33 extends annularly therefrom and is arranged to be assembled against the end of the ring 28 of the casing, and suitable bolts 36 extend 50 through the flange 35 and are screwed into threaded openings in the ring 28 to detachably secure the section B of the vaporizer with section A.

A closed brine containing receptacle is arranged to extend interiorly of the casing 31 and forms a part of the vaporizer. Such receptacle includes a cuprous casing 37, which is preferably annular and extends substantially the entire length of the casing 31. The casing 37 is preferably annular in cross section and is of a diameter such that it will be spaced annularly of the casing 31. The inner end of the casing is supported in such spaced relation with the casing 31 by bosses 38, which 65 are formed to extend inwardly from the cas-

ing 31. The inner end of the casing 37 is closed by a cup-shaped member 39, and the end 40 of the casing 37 is bent back over the edge of the end member 39 and is secured in leak-proof relation therewith by solder or other suitable means. A ring 41 extends inferiorly of the outer ends of the casings 31 and 37, and is provided with an annular peripheral groove 42, into which the ends of the casings 31 and 37 are pressed and secured by solder 43, providing a leak proof connection for the end of the casing 31 and for the end of the casing 37. The end of the ring 41 is provided with an annular flange 44, which is closed by an end plate 45 secured to the outer face thereof by bolts 46. The end plate 45 is provided with a central passage 47, into which a tube 48 is secured and extends inwardly of the casing 37, the inner end of the tube 48 being closed. Such tube provides a means for the insertion of a thermometer, so that the temperature internally of the casing 37 can be ascertained when desired.

A plurality of annular brace members 49 are provided at spaced intervals interiorly of the casing 37 and are arranged to bear against the interior wall of the receptacle to prevent buckling thereof, due to excessive pressures which will exist within the casing 31 when under test. The brace members 49 are provided with central apertures to permit convection of the brine within the receptacle 37 when the refrigerant is boiling.

The refrigerant and lubricant are constantly sustained automatically at a level substantially horizontal with the lower portion of the openings 27 in the outlet tube within the casing 10 and the casing 31, so that the casing 37 is substantially surrounded and submerged in the refrigerant. The outlet opening 20 is preferably arranged in a horizontal plane below the top of the section B, so that there will be a space above to receive vaporized refrigerant rising from the liquid refrigerant along the entire length of the section.

It will be seen that the structure herein described is of a rugged nature, such that it will withstand the pressures caused by evaporation of the refrigerant, and that it can be readily assembled and cheaply manufactured. The structure also has the further advantage of manufacture in that a standard section A can be used and various sizes of sections B can be assembled with the section A to suit the various sizes of rooms and conditions, thus providing a simple and economical manner of manufacturing vaporizers of different sizes. By utilizing a plurality of sections, one can be of sufficient diameter to contain the valve mechanism while the other section can be reduced in diameter and with the brine receptacle therein the quantity of refrigerant required in the vaporizer is materially reduced. The brine receptacle internally of the vaporizer is affected by the

temperature of the refrigerant and reacts thereon to delay the operative and inoperative periods of the compressor operation when controlled by suction pressure as set forth in my co-pending application herein mentioned.

Various changes may be made in the details of the construction of the embodiment as herein described, without departing from 10 the invention and the scope of the appended claims.

I claim:

1. A vaporizer of the flooded type comprising a plurality of communicating sections, 15 one of said sections having refrigerant inlet and outlet passages in its wall, and a brine containing receptacle within the other of said sections and arranged in spaced relation with the internal wall thereof.
- 20 2. A vaporizer of the flooded type comprising a pair of communicating sections secured together in endwise relation, refrigerant inlet and outlet passages extending through the wall of one of said sections, and a 25 brine filled receptacle extending substantially the length of the other of said sections and secured therewith in spaced relation with the internal wall thereof, said section within which said brine receptacle extends being detachably secured with the other section.

3. A vaporizer of the flooded type comprising a pair of communicating sections detachably secured together in endwise relation, said sections being of different transverse 35 sections, the larger of said sections being provided with inlet and outlet refrigerant passages in its wall and having a float controlled valve associated interiorly thereof with the inlet passage, and the smaller of said sections having a brine receptacle secured therein and arranged in spaced relation with the interior wall thereof.

4. A vaporizer of the flooded type comprising a plurality of communicating sections secured together in endwise relation, a brine 45 receptacle within one of said sections and secured thereto, and a tube having a closed end extending interiorly of said brine receptacle.

5. A vaporizer of the flooded type comprising a pair of communicating sections secured together in endwise relation, one of 50 said sections being relatively longer and of smaller section than the other section, a brine containing receptacle extending interiorly substantially the full length of the elongated section and spaced from the interior wall thereof, and a plurality of spaced bracing means within said brine containing receptacle to prevent buckling of said receptacle under 60 pressure.

6. A vaporizer of the flooded type comprising a pair of communicating sections secured together in endwise relation, one of said sections being of smaller section than the other 65 of said sections, a brine containing receptacle

extending substantially the full length and spaced from the interior wall thereof, and a plurality of brace members arranged in spaced relation interiorly of said receptacle to prevent buckling under pressure, said brace members having passages through the central portion thereof to permit convection of the brine within said receptacle.

7. A vaporizer of the flooded type comprising a pair of communicating sections arranged in endwise relation, rings secured in leak proof relation with the adjacent ends of said communicating sections, and means for detachably securing said rings together.

8. A vaporizer of the flooded type comprising a pair of cylindrical cuprous communicating sections secured together in endwise relation, one of said sections having refrigerant inlet and outlet passages extending through a wall thereof and means for maintaining a constant refrigerant level therein, the other of said sections being of reduced section and arranged concentrically with the first mentioned section, said reduced section being of materially greater length than the other section, and a brine containing receptacle secured within said smaller section and extending substantially the full length and in spaced relation with the internal wall thereof.

9. In mechanical refrigerating apparatus, a vaporizer of the flooded type comprising a plurality of hollow sections assembled substantially in axial relation, the adjacent ends of said hollow sections being open, means for securing said open ends of said sections together in leak proof relation, one of said sections having a refrigerant inlet and outlet port, and means within one of said sections for materially reducing the internal refrigerant capacity thereof.

10. A vaporizer structure for mechanical refrigerating apparatus comprising a plurality of tubular sections arranged endwise to form a laterally extending interior chamber, the adjacent open ends of said tubular sections providing a common inlet and outlet for the passage of refrigerant therebetween, means for securing said sections together in leak proof relation, and inlet and outlet refrigerant ports in one of said sections.

11. In a mechanical refrigerating apparatus, a vaporizer connected in circuit comprising a plurality of tubular sections associated in endwise relation to provide an interior chamber extending in substantially a horizontal plane, the ends of adjacent sections being open to provide a common passage therebetween for liquid and vaporized refrigerant, a portion of the passage extending in a plane above the refrigerant level, means for securing said sections together, and means in one of said sections for automatically maintaining a constant level of refrigerant in said chamber.

12. A vaporizer structure for mechanical refrigerating apparatus comprising a plurality of communicating sections of different external area adapted to be associated end-
wise to form a laterally extending chamber,
5 an inlet port in the largest section, a float controlled valve mechanism in the largest section for maintaining a constant level of liquid refrigerant within and partially filling
10 said chamber, a refrigerant outlet port in one of the sections above the liquid level therein, and means for securing said sections together in leak proof relation.

15 In testimony whereof, I hereunto affix my
signature.
